United States Patent Office.

HENRY BOWERS, OF ALBANY, NEW YORK.

Letters Patent No. 77,575, dated May 5, 1868.

IMPROVEMENT IN DRAUGHT AND SHAFT-TUGS.

The Schedule referred to in these Letters Patent and making part of the same.

TO ALL WHOM IT MAY CONCERN:

Be it known that I, HENRY BOWERS, of Albany, in the county of Albany, and State of New York, have invented a new and improved Draught and Shaft-Tug; and I do hereby declare that the following is a full, clear, and exact description thereof, which will enable others skilled in the art to make and use the same, reference being had to the accompanying drawings, forming part of this specification, in which—

Figure 1 is a perspective view of my invention.

Figure 2 is a central longitudinal section, taken at right angles to the shaft.

Figure 3 is a view of steel plate, to which one end of the tug is fastened.

Figure 4 is a perspective view of shaft-clasp.

Figure 5 is a sectional view of shaft-tug and clasp, taken on the plane of the line $z z$; fig. 2.

Figure 6 is a surface view of wedge E, fig. 2.

Similar letters of reference indicate like parts.

The object of my invention is to provide an easy and safe method of attaching horses or other draught-animals to a vehicle, for the purpose of drawing the same. This object I accomplish by means of a shaft-clasp and tug, as will be hereinafter more fully described.

Another object of my invention is to dispense with breeching, traces, and whiffle-tree, which are rendered unnecessary by the use of my invention, as will be hereinafter more fully shown.

My invention consists in the construction of a shaft-clasp, B, and a draught or shaft-tug A. The clasp B is made of iron or other suitable metal, and of the form shown in figs. 2, 4, and 5. Said clasp may be made of one piece of metal, or of two, as shown in fig. 4, having its lower parts dove-tailed, as shown in same figure, so that it may fit different-sized shafts. Said clasp B has three screw-holes in it, and is fastened to the shaft by screws f, as shown in fig. 2.

The tug A is also made of iron or other suitable metal, and of the shape shown in fig. 2. That portion of the tug which embraces the clasp B is made of a curved or circular form, so as to fit snugly to the clasp B, as shown in fig. 5. The tug A is made of two pieces of metal, and united by a hinge, as shown at l in fig. 2. The lower piece of the tug is provided with a thumb-screw, L, and the upper piece with a slot, L', of corresponding shape, to pass over the head of the thumb-screw L, as shown in fig. 2. The upper end of the tug is fastened to the saddle F by means of two screws, i i, passing through the tug, the lower end of the saddle, and a steel plate, D, with its brass nuts, k k, fastened to it, as shown in fig. 2. The lower end of the tug is provided with a strap, J, which is buckled to a belly-band for the purpose of keeping the tugs on each side of the horse from flying up.

Should the shaft be so large as to keep the lower ends of the tug A from closing under the thumb-screw L, I insert a wedge, E, between them, as shown in fig. 2.

D designates a steel plate, placed under the saddle, between it and the pad k, as shown in fig. 2. This plate is fastened, at its upper end, to the gig-tree at the top of the saddle, by means of four rivets, passing through holes marked b, and also by the screw at the bottom of the terret-shank, passing through opening a, as shown in fig. 3. The lower end of this plate has apertures e e and brass nuts k k, which are fastened to the plate, and through which screws i i pass, to fasten the tug A to the saddle, as shown in figs. 2 and 3.

A, l, in fig. 2, is shown a short bolt, with its nut, by means of which is attached one end of the breast-collar G, as shown in fig. 1.

The arrangement of the saddle F, breast-collar G, neck-piece H, tug A, and shaft C is clearly shown in fig. 1.

It will be seen, from the above, that breeching, traces, and whiffle-tree are unnecessary articles where my invention is used, and there is also less danger in attaching a horse to a vehicle with my invention than by the old method.

From the above it will be seen that the mode of operation of my invention will be as follows: The draught-tug A having been fastened to the saddle F, and connected to the breast-collar G, with its neck-piece H, they are put upon the horse, and the belly-band I buckled, all as shown in fig. 1. The animal is then placed between

the shafts at the right distance from the carriage or other vehicle. Thus we find the place on the shaft where we must screw fast the clasp, B. The clasps having been once put on in their right places, may remain there. Then, when we want to attach the horse to the shafts, we have only to raise the upper hinged part of the tug, place the shaft in its place, bring down or close the tug, then turn the thumb-screw L across the slot L', to secure it firmly in its place.

Having thus described my invention, its nature and construction, what I claim as new, and desire to secure by Letters Patent, is—

1. The shaft-clasp B, substantially as shown and described.
2. The tug A, substantially as shown, and for the purpose set forth.
3. The combination of shaft-tug A with saddle F, breast-collar G, and shaft C, substantially as and for the purpose set forth.

HENRY BOWERS.
